UNITED STATES PATENT OFFICE

THEODORE KLAHRE, OF UNION CITY, NEW JERSEY, ASSIGNOR TO CONSOLIDATED TRIMMING CORP., OF NEW YORK, N. Y., A CORPORATION OF NEW YORK

BULLION-FRINE Loom APPARATUS

Application filed October 17, 1929. Serial No. 400,370.

Generally the invention relates to novel and useful improvements in the construction and consequent mode of operation of bullion-fringe loom apparatus of the type capable of producing simultaneously a number of widths of fringe by having groups of warp threads spaced apart and weft threads adapted to be interwoven respectively with each of said groups of warp threads. In such looms it is customary to mount the hooks on the lay and to move all the hooks by positive actuating mechanism carried on the lay and partaking of the swinging of the lay.

The invention relates particularly to a driving and connecting mechanism affecting the lay and a member of the hook operating mechanism such that the backward and forward motion of the lay directly, without the interposition of cumbersome and power-consuming gearing and other motion communicators and converters, actuates the hook operating mechanism to reciprocate longitudinally of the lay and at the same time to partake of the swinging movement of the lay.

It is the general object of my invention to improve the construction of a loom of the character described by means already mentioned and to be specifically described herein-after such that it becomes capable of operating at very high speed with a minimum of vibration.

A further and incidental object of my invention resides in the structure of the driving and connecting mechanism affecting the lay and a member of the hook operating mechanism on the lay such that control, adjustment, actuation and timing or synchronization of the hook operating mechanism in coaction with the lay is more readily and simply accomplished and such that the parts may be more easily constructed and more readily accessible for repairs.

These objects and other advantageous ends in the arrangement and combination of parts to which my invention relates are now to be described, reference being had to the accompanying drawings, wherein like reference characters designate corresponding parts throughout all the views.

Fig. I is an end elevation of a bullion-fringe loom, partly in section, and shows my invention thereon.

Fig. II is a top plan view, partly in section, of the loom shown in Fig. I.

Fig. III is a sectional end elevation taken along the line III-III in Fig. II.

Fig. IV is a fragmentary plan view, partly in section, illustrating certain of the features of my invention.

Fig. V is a fragmentary end elevation, partly in section, illustrating certain of the features of my invention.

Fig. VI is a fragmentary end elevation, partly in section, illustrating the position of the elements of my invention during the operation thereof.

1 represents the frame of a bullion-fringe loom of known construction, and comprises the usual elements which are partially represented in Figs. I and II. 2 is a breast beam affixed to the upper bases of the foremost uprights of frame 1 and is partially represented in Fig. I. Guide rods 3, only one of which is shown in the accompanying drawings, each similarly spaced and secured oppositely to the upright of frame 1, serve as the mount for lay 4. The said lay 4 is provided with sleeved bores 5 through which pass guide rods 3, the latter serving as bearing shafts for the lay when it is actuated to oscillation. Guide rods 3 are deviations from the usual manner of mounting the lay pivotally from the frame of the loom, and effectuate or confine oscillation of the lay in the plane of the horizontal, thus eliminating stress and strain factors from the frame of the loom caused by the turning moments of the lay in its oscillations. There being an intimate relation between vibratory phenomena and the action of divers physical forces on any particular body, it can be said at this time that the mounting of lay 4 on guide rods 3 as above described contributes in the arrangement and combination of parts of my invention toward the minimization of vibration of the frame of the loom, especially where the loom operates at high speed, and toward the functioning and operation of the driving

and connecting mechanism, all of which will be fully described hereinafter.

6 are suitable standards utilized in a bullion-fringe loom of the type herein, being 5 secured to lay 4 and positioned in alignment and at definite intervals. Standards 6 have reeds 7 secured thereto through which pass the warp threads of the various fringes; the warp threads for each width of fringe being 10 arranged in groups 8 as clearly shown in Fig. II of the accompanying drawings. Wefts 9, each arranged adjacent to the warp threads for every width of fringe, constitute the material for the strands of bullion in the manufacture of the various fringes. The warp threads are actuated in the customary manner 15 for the production of sheds by heddle frames 10, the operating means for the heddle frames not being illustrated in the accompanying drawings. Wefts 9 are similarly actuated by 20 a heddle frame, not shown in the accompanying drawings, to raise and lower them in and out of the path of a hook passing through each warp shed in a manner and for a purpose to 25 be hereinafter described.

Bar 11 is slidably mounted on lay 4, and secured thereon by means of uprights are weft-inserting members or hooks 12 spaced between each two of the adjacent warp thread 30 groups 8 to engage the weft for the respective warp thread groups. Lay 4 is moved to produce the beat-up of the weft, and more particularly in its application to my invention, to directly actuate slide bar 11 to reciprocate longitudinally of the lay. Lay 4 is moved for these purposes by any suitable 35 means such as a connecting rod 13 which is actuated by a crank pin 9' positioned in a slot 14 on a variable speed driving toothed wheel 40 15. Toothed wheel 15 is secured to the main shaft 16, and derives its motion from the main drive by pulleys or gears not illustrated in the accompanying drawings.

Proceeding now to a description of the features of the driving and connecting mechanism inclusive of structural details, co-operation, combination, and arrangement of the several parts, reference is had to Figs. III-VI inclusive, of the accompanying drawings.

56 17 and 18 are appropriately shaped guide rods secured to brackets 19 and 20, both the latter being affixed to an upright of frame 1 and the breast beam 2 respectively; the said guide rods being so positioned together as to 55 comprise a cam groove to engage a grooved wheel 21. Grooved wheel 21 is revolvably mounted on spindle 22, the latter being secured to and near the extremity of slide bar 11. 23 is a roller revolvably mounted on spindle 22 and positioned above grooved wheel 21, the said roller running along a longitudinal 60 guide-way. 25 is a bracket forwardly and horizontally flanged and supported by uprights 26, the said bracket 25 being provided 65 on the flange with rectilinear slot 28 to serve

as the aforementioned guide-way for roller 23. Slot 28 is of a length equal to the longitudinal displacement of grooved wheel 21 by virtue of its engagement with guide rods 17 and 18, the extremities of the slot being in line 70 with the thrust limits of the said guide rods 17 and 18.

In order to permit revolution of grooved wheel 21 in the cam groove, sufficient clearance is provided as best illustrated in Fig. III of 75 the accompanying drawings. When slide bar 11 is actuated to oscillate in the right direction, grooved wheel 21 rolls along guide rod 17 as a track and partakes of the longitudinal displacement effected by the shape of the said guide rod 17. The reactive force of the said guide rod 17 forces grooved wheel 21 and slide bar 11 to which it is secured to move to the right and longitudinally of lay 4. On the return movement in the oscillation of slide bar 80 11, grooved wheel 21 rolls along guide rod 18 forcing grooved wheel 21 and the slide bar to move to the left and longitudinally of the lay. And further to effect revolution of roller 23 in the guide-way or slot 28, slight clearance 85 is provided in the width of the said slot, as illustrated in Fig. III of the accompanying drawings.

In reference to guide rods 17 and 18 comprising the cam groove for grooved wheel 21, 90 appropriately shaped rods may be employed to control the amplitude and differential timing of slide bar 11 in its reciprocation longitudinally of the lay, it being evident that for the portion of the cam groove that forms the 95 more acute angle with the line of the horizontal, slide bar 11 will travel the faster, and that for the portion of the cam groove that is perpendicular to the line of the horizontal, slide bar 11 will not reciprocate or oscillate at all. 100 At this time, such provision in my invention has significance in that slight lag may be afforded for operations performed on the return movement of lay 4. At the backward movement of lay 4 in the oscillation or reciprocation of the same, hooks 12 pass through the 105 warp sheds of the various warp thread groups 8 to engage wefts 9. On the return and forward movement of lay 4, hooks 12 carry wefts 9, constituting the material for the strands of 110 bullion in the manufacture of the fringes, to be interwoven respectively with each of said 115 groups of warp threads and to form bullion strands therefor. Usually, simultaneously with the formation of the respective bullion 120 strands, the beat-up of wefts 9 in the respective warp thread groups 8 is produced by reeds 7 laterally secured to standards 6, the latter being affixed to lay 4. A knocking device, which is not illustrated in the accompanying 125 drawings, disengages the respective bullion strands from hooks 12 at about the same time. Thus it is manifest that a lag at this point regardless of the reciprocating speed of lay 4 is salutary. Where a certain 130

variety of weft requires a twisting mechanism to twist the bullion stands, this operation is done before the knocking device comes into play. A twisting device is not illustrated in the accompanying drawings, nor is the mechanism for rolling the respective bullion-fringes illustrated in the accompanying drawings. The advantages of guide rods 17 and 18 comprising the cam groove in reference to the minimization of vibration and the increase in the number of picks per unit time will be set forth hereinafter.

The operation of the foregoing driving and connecting mechanism comprising the improvements of my invention as to structure, co-operation, combination and arrangement of parts, is fairly simple. Variable speed driving toothed wheel 15 communicates reciprocating motion to lay 4 by connecting rod 20 13 which is actuated by adjustable crank pin 9 positioned in slot 14 to regulate the amplitude of lay 4. Lay 4 reciprocates in the plane of the horizontal sliding about guide rods 3. The reciprocation of lay 4 actuates the reciprocation or oscillation of slide bar 11 thereon longitudinally of the lay by virtue of grooved wheel 21 engaged by a cam groove comprised of guide rods 17 and 18. The operation of hooks 12 actuated by slide bar 11 to engage and carry respective wefts 9 have been heretofore described. The coaction between lay 4 and slide bar 11 is perfectly synchronized by virtue of structure irrespective of frequency in the oscillation of lay 4. Such synchronization or timing is significant; for at one limiting position of lay 4 hooks 12 function to engage respective wefts 9, and at the other limiting position, reeds 7 produce the beat-up of the respective wefts, while a knocking device almost simultaneously therewith disengages the bullion strands from the respective hooks 12. If a twisting mechanism is employed, hooks 12 are twisted the instant before the disengagement of the bullion strands by the knocking device. For high frequency of lay 4 a twisting mechanism is not employed; such a device being unnecessary for certain varieties of weft.

By the utilization of means other than the driving and connecting mechanism as heretofore described, synchronization between lay 4 and slide bar 11 is precarious when the bullion-fringe loom apparatus operates at higher speed. Under such circumstances slide bar 11 is actuated to oscillate by mechanisms comparatively unassociated with lay 4 such as cam-operating treadles, springs in conjunction therewith, gearing and other motion communicators and converters. The said mechanisms usually interposed, as above-mentioned, to actuate slide bar 11 to synchronize with the movement of lay 4 are power-consuming, massive and vibratory, the functioning thereof at high speed for pur-

poses of synchronization being influenced by friction, dislocation, jamming and inertia of the several parts. The mechanisms for actuating slide bar 11, moreover, are productive of vibratory movement, and the same is communicated to frame 1 of the bullion-fringe loom to which they are secured.

The quality of the manufactured fringes is seriously impaired by the vibration of the operative parts of the loom apparatus in the production of the said fringes. My improved driving and connecting mechanism comprises features doing away with this vibration at both low and high speed in the particulars heretofore set forth and also in the functioning of roller 23 associated with slot 28. Roller 23 prevents angular backward and forward tilting displacement of slide bar 11 in the groove of lay 4, and prevents jamming of grooved wheel 21 in the cam groove during operation.

From the foregoing description, the improved driving and connecting mechanism affecting lay 4 and a member of slide bar 11 comprises a minimum of simple and inexpensive parts, the latter being easy of adjustment and control, and being readily accessible for repairs and easy replacement.

The number of picks per unit time, utilizing my invention, has been increased three-fold (and may with security extend beyond this) with the production of the finest quality of fringe. Vibration of the loom has been set to a minimum for both low and high speeds by virtue of all of the foregoing features present in the invention.

Economically, less power is consumed, less noise is generated, the production is manifoldly increased, and the bullion-fringe loom apparatus becomes more simple and comprises fewer parts, all by virtue of my invention. The attendant is freed from facing a complex structure of a complex bullion-fringe loom.

I wish it understood that the embodiment of my invention is solely for purposes of disclosure herein and that there is no limitation to any specific construction in the disclosure; minor changes in size, shape and arrangement of parts, variations and modifications of details may all be resorted to without departing from the spirit of my invention nor enlarging its scope within the appended claims.

Having described my invention, what I now claim as new and desire to secure by Letters Patent of the United States is:

1. In a bullion-fringe loom for weaving a plurality of fringes having groups of warp threads spaced apart and weft threads adapted to be interwoven respectively with each of said groups of warp threads, a lay, means for the mounting and sliding of same in the plane of the horizontal, a slide on the lay to actuate weft inserting means, means to oscil-

- late said lay, and an actuating mechanism comprising a guide having an appropriately shaped slot, a roller engaging the slot and journaled on the slide, the said guide and roller being adapted to impart reciprocating motion to the slide directly from and longitudinal of the motion of the lay, the slide at the same time partaking of the swinging movement of the lay.
10. 2. In a bullion-fringe loom for weaving a plurality of fringes having groups of warp threads spaced apart and weft threads adapted to be interwoven respectively with each of said groups of warp threads, a lay, fixed bearing shafts in spaced relation to the lay for the mounting and reciprocation thereof in the plane of the horizontal, a slide on the lay to actuate weft inserting means, actuating means to oscillate said lay at variable frequencies, an actuating mechanism comprising appropriately shaped rods fixed and in spaced relation to form a cam groove, a roller engaging the groove and journaled on the slide, the said actuating mechanism being adapted to impart reciprocating motion to the slide directly from and longitudinal of the motion of the lay, means to prevent angular motion of the slide on the lay.
30. 3. In a bullion-fringe loom for weaving a plurality of fringes having groups of warp threads spaced apart and weft threads adapted to be interwoven respectively with each of said groups of warp threads, a lay, fixed bearing shafts in spaced relation to the lay for the mounting and reciprocation thereof in the plane of the horizontal, a slide on the lay to actuate weft inserting means, actuating means to oscillate said lay at variable frequencies, an actuating mechanism comprising 40. appropriately shaped and removable rods fixed and in spaced relation to form a cam groove, a roller revolvable on a spindle positioned and secured on the slide, the said actuating mechanism being adapted to impart reciprocating motion to the slide directly from and longitudinal of the motion of the lay, means to prevent angular motion of the slide on the lay.
50. 4. In a loom of the character described, a lay, guides upon which the lay is laterally movable, a supporting bar slidably mounted on and having guided movement longitudinally of the lay, a roller on the bar, and a fixed guide near one end of the lay, in which 55. the roller moves to reciprocate the bar when the lay is laterally oscillated.

In testimony whereof, I have hereunto affixed my hand this 15th day of October, 1929, at 1440 Broadway, in the city, county and State of New York.

THEODORE KLAHRE.
